UNITED STATES PATENT OFFICE

KARL F. NYSTROM, OF CHICAGO, ILLINOIS

CAR-WINDOW CONSTRUCTION

Application filed January 15, 1927. Serial No. 161,390.

My invention relates to an improved window construction for railroad passenger cars, street cars and interurban cars; the invention having for its object the provision of a construction, controllable by the occupant of the seat or berth whereby suitable ventilation and ingress of air may be obtained; while at the same time providing a construction whereby a maximum vision is obtained in a given window opening and a suitable avenue is provided to permit communication between the occupant of the car and an individual on the outside without necessitating opening of the outside window.

15 The objects and advantages of my invention will be readily comprehended from the following detailed description of the accompanying drawings, wherein—

Figure 1 is an inside elevation of a section 20 of railroad car provided with my improved window construction, with the floor shown in section and the underframe omitted.

Figure 2 is an outside elevation of a pair 25 of windows,—partially broken away as is also true of the side wall of the car.

Figure 3 is a vertical section of my improved window construction.

Figure 4 is a perspective view of a portion 30 of the upper end of a window screen employed with my improved construction.

Figure 5 is a sectional plan of my improved window construction.

Figure 6 is a sectional plan of the window-sill.

35 Figure 7 is a sectional view taken substantially on the line 7—7 of Figure 5 looking in the direction of the arrows.

My invention contemplates an improved window construction involving a frame 40 adapted to receive double window-sashes, namely an outer sash and an inner sash, while the ledge portion of the frame is formed to provide an air chamber having air ducts or passages open to atmosphere.

45 The invention also contemplates means whereby the outer window is pivotally secured in place; while the inner window involves means operable from the car interior whereby easy and positive operation of the 50 inner window by the occupant may be had;

while at the same time simultaneous positioning of a window-screen may be accomplished.

As my invention is more especially intended for use in connection with sleeping cars, 55 the exemplification discloses a section of a sleeper, namely with the opposing seats being shown at 15, 15, in Figure 1, arranged, as usual, adjacent to a pair of windows generally indicated at 16, 16 in said figure, with 60 the window at the left being shown partially raised and the opening therebeneath provided with a suitable mesh screen indicated at 17.

In Figure 3, 18 and 19 represent portions 65 of the outer and inner car walls, spaced apart as usual and provided with an opening to receive my improved window frame construction 20, having an opening in the top to permit passage of the inner window-sash 21 when the latter is raised.

70 The inner window-sash 21 at one side is preferably provided with a rack 22 and a bearing roller 23; while the opposite side of the sash is also shown provided with a bearing roller 24 which is preferably supported 75 by an upwardly disposed projection 25 formed on the upper end of the inner sash to receive any thrusts that may be encountered in the operation of the window.

The side portion of the frame 20, which is 80 preferably of metal, is formed to provide a sash receiving groove or channel 26 of depth sufficient to receive the bearing rollers as well as a portion of the side members of the window-sash. The frame 20 is also formed to 85 provide the intermediate bent portion whereby an abutting shoulder 27 is provided for the outer sash 28, which is thereby maintained in spaced relation with the inner sash 21.

85 The car interior side of the window-frame 20 is also formed with a small vertically disposed groove or socket at 29 to provide a slide-way for the side frames of the window-screen 17; the grooves 29 being arranged in close proximity to the window slide-way, as 90 shown in Figure 5.

The frame member 20 at the right in Figure 5, at a point coincident with the channel 26, and preferably adjacent to the upper end of the inner window-sash 21, is provided with a 100

suitable opening for passage of a segment or portion of a pinion 30 in order that the latter may mesh with the rack 22 formed on the adjacent side of the inner window-sash. The 5 pinion is mounted in the car side wall by means of a suitable bracket as at 31 in Figure 5; with the journal of the pinion extending through to the car interior where it is formed to receive a crank 32.

10 It is apparent that the inner window 21 may be easily raised or lowered by proper operation of the crank 32 and that the rollers 23, 24 will hold the sash against lateral movement and cause the window to slide easily.

15 The lower part or ledge of the window frame comprises a hollow or chambered portion 33. The extreme ends of this chamber are open at 34, 34 to the car exterior; the openings being preferably disposed in a direction substantially parallel with the car sides. The ledge 33 has its largest cross-sectional area at the ends 34, and gradually tapers or slopes upwardly toward the center of the window-opening, forming two opposing funnels or ducts. The passage through the hollow member 33 is considerably reduced at the upper intermediate point 35 in order to create pressure when air is forced or passes through the openings 34. The intermediate portion 35 is horizontally disposed and has its top provided with a suitable number of holes or slots 36. These openings or slots 36 are arranged to be directly underneath the inner sash 21 when the latter is in closed position. 20

25 When the inner window 21 is in open position, these perforations 36 will be uncovered; and due to the funnel-shape of the chamber 33, the air entering the chamber will be forced into the interior of the car. The inner or car side of the ledge of the window frame is formed to provide a housing 37 for the roll screen 17. This screen housing 37 is provided with a removable wall or cover 38, secured in place by screws or other suitable means whereby a smooth surface is provided; the top of housing 37 being provided with a slot for passage of the flexible screen therethrough.

30 The upper part of screen 17 (shown in Figure 4) projects through the opening or slot in the housing 37 and is exposed on the interior of the car; the top of the roll screen being provided with a flanged top 17^a which overlaps and rests upon the ledge of the window frame. A suitable link or hook 39 is attached to the flanged top or upper portion of the screen. This link 39 is adapted to engage or hook onto a bracket 40 secured to the lower portion of the inside sash 21.

35 If ventilation is desired, the attendant or passenger operates crank 32, thereby raising the inside sash 21. Raising of the sash 21 will uncover the openings or slots 36 and allow air from the car exterior to rush into the car. If it is desired to exclude dust and cim-

ders from the car interior, link 39 of the roll screen 17 is hooked onto the bracket 40 before raising the window, thereby causing the screen to automatically follow the upward movement of the sash 21; the screen covering the window opening so that the air coming through the passages or ports 36 will also be caused to pass through the screen 17.

40 A further purpose in tapering or sloping the air chamber 33 is to provide a self-cleaning ventilator. It will be seen that by sloping or disposing the outer ends of the chamber 33 downwardly toward the openings 34, any cinders or foreign matter entrained with the inrushing air will be caused to automatically discharge from the chamber through the open ends 34.

45 With the openings 34 at each end of the ventilator preferably the same, while the chamber at the center is considerably reduced, it is apparent that with movement of the air on the car exterior and therefore past the chamber that air will rush in one end of the ventilator, while the outer air rushing past the opposite end will form a vacuum at the last mentioned end, thereby causing dust and other foreign matter to be withdrawn from the ventilator.

50 The outside window 41 is pivotally attached to the upper portion of frame 20 in any convenient manner and preferably held in place at its bottom by means of a butterfly nut 42 which engages a forked bracket 43 which may be secured to or engages the lower end of the outer window sash 41 and preferably at an intermediate point. The fork or lower slotted end of the bracket 43 provides passage of the screw element or bolt 44 which is pivotally secured at 45 to a suitable bracket 46 secured on the ledge of the window frame 20 on the car exterior; the outer or free end of the element or bolt 44 being preferably provided with an enlargement or head to prevent removal and accidental loss of the butterfly-nut 42.

55 The outer flanges 47 of the window frame 20 are provided with brackets 48, 48 for holding adjustable deflectors 49 and permit them to oscillate laterally. On a sleeping car where two windows are close together, three deflectors for each section are preferably provided. These deflectors are preferably pivoted on suitable brackets 48 to swing about a vertically disposed axis and rattling or undue motion thereof prevented for example by means of any suitable spring tension providing means. With these deflectors thus yieldingly held in place, they will adjust themselves to the proper angle relative to the direction of movement of the train after the train is in motion and will deflect dirt and cinders from the window opening.

60 In providing the openings or slots 36 at the predetermined point in the top of the window ledge as shown in Figure 3, it is ap-

parent that the inner sash or window will constitute a closure for said openings and prevent ingress of air between the inner and outer sashes when the inner window is in closed position and thus still maintain the weather sealing function of the double windows. It will be understood, of course, that the roll-screen is spring controlled so as to normally roll up on its roller when the inner window is lowered; the constant spring tension maintaining the link 39 on the bracket or hook 40 until it is purposely released by the operator.

The invention has been described in terms employed merely as terms of description and not as terms of limitation, as structural modifications may be made without, however, departing from the spirit of my invention.

What I claim is:

1. In a car window construction involving an upwardly sliding window sash, a window frame, the ledge portion whereof beneath the sash supporting face is formed to provide a chamber within the ledge disposed lengthwise thereof and terminating in outwardly curved and oppositely disposed ends open to the car exterior, the intermediate upper portion of the ledge on which said sash rests being apertured whereby communication with said chamber within the ledge is established when the window sash is raised from said ledge.

2. In a car window construction involving a window sash, a window frame having a ledge provided with a chamber lengthwise therein, said chamber terminating on the car exterior in oppositely disposed open ended ducts, while the top of the ledge intermediate of the inner and outer sides thereof is provided with openings communicating with said chamber; said openings being coincident with the bottom of the sash and closed thereby when the sash is in closed position.

3. In a car window construction involving a window sash, a metallic window frame, the ledge portion whereof is formed hollow to provide an air chamber having openings on the car exterior side of the ledge disposed in opposite directions lengthwise of the car, while the top of the ledge coincident with the bottom of the window sash is provided with openings communicating with said air chamber so as to be normally closed by the sash.

4. In a car window construction, a window sash, a hollow window frame, the ledge portion whereof is chambered to provide downwardly and outwardly disposed ducts extending substantially parallel with the car outer wall and having open ends, said ducts converging in an air chamber adjacent to the top of the ledge, the top of the ledge having openings at points coincident with the bottom of the window sash so as to be normally closed thereby.

5. In a car window construction, a window frame provided with a hollow ledge formed to provide an air chamber having downwardly and outwardly curved ends extending to the ledge exterior and in opposite directions parallel with the car outer wall, the intermediate upper portion of said chamber extending horizontally and having an upwardly disposed outlet through the ledge.

6. In a car window construction, a ledge commensurate with the thickness of the car wall and formed to provide a pair of chambers disposed lengthwise thereof, one of said chambers constituting an air receiving chamber having downwardly and outwardly flaring ends arranged on the car exterior and disposed in opposite directions, the ledge in its top having openings communicating with the intermediate portion of said air chamber, while the other chamber is adapted to hold a roll screen, the car interior side of said ledge being provided with a removable wall to permit access to said last mentioned chamber.

7. In a car window construction, a window frame the ledge whereof is hollow to provide an air chamber having outwardly flaring ends opening in opposite directions on the car exterior, ports in the top of the ledge communicating with said air chamber, said ports being disposed in the window sash holding portion of the ledge to be normally closed by the window sash.

8. In a car window construction, a window frame formed to receive a vertically slideable window-sash, the ledge of said window frame being hollow and formed on the car exterior side thereof with upwardly extending ducts tapering inwardly and terminating in an air chamber in the upper part of said ledge, the top of the ledge having openings communicating with said air chamber and disposed at a point coincident with the lower part of the window sash to be normally closed thereby.

9. In a car window frame construction, the ledge whereof beneath the sash holding upper face is provided with a horizontally disposed chamber in the upper intermediate part and having upwardly disposed ports coincident with the sash engaging portion for discharging air into the car, when the sash is raised, and ducts extending lengthwise in the car exterior side of the ledge terminating in open ends disposed in opposite directions and communicating at their inner ends with said chamber.

KARL F. NYSTROM.
